Inventor:

Karl Dehne,

By Paul E. Schilling,

Attorney.

UNITED STATES PATENT OFFICE

KARL DEHNE, OF BURGSTADT, GERMANY

MOLDING APPARATUS FOR MAKING DENTURES AND PLATES FOR DENTAL PURPOSES

Application filed November 28, 1928, Serial No. 322,408, and in Germany September 17, 1928.

My invention concerns a molding or casting apparatus operated by compressed air and intended for use in making dentures and plates for dental purposes. The invention consists substantially in this, that I provide a mechanical device by means of which a pressure reservoir adapted to receive molding cylinders or the like, of various height, and its appurtenant cover are moved 10 in opposition to each other and allowed to press against each other so that the compressed air passed into the reservoir or container, instantly acts upon a plurality of molding cylinders so that several dentures 15 may be made in one single operation.

The invention will be more clearly understood by referring to the accompanying drawing in which,

Fig. 1 gives a front elevation of the molding machine, showing a cross-section of the cover and pressure reservoir,

Fig. 2 gives a side view.

The apparatus consists of two racks *a* and *b* in which engage two pinions *c* and *d*, 25 which may be rotated by a hand wheel *e* thus imparting an up and down motion to the racks.

The upper connecting yoke of the racks carries the cover or hood *f*.

When the hand wheel *e* is suitably rotated, the racks *a* and *b* are lowered and thus the cover *f* is forced against the pressure reservoir *g*, in which the molding cylinders *k*, *l*, are to be found.

Upon the cover and the pressure reservoir being thus sealed together and compressed air admitted through the hollow standard *b*, into the bell-shaped space *h*, this air passes through the various holes 40 in a perforate partition or baffle plate *i*, in the cavity of the bell-shaped cover to the reservoir and thus acts upon the molding cylinders *k*, *l*, situated therein. These cylinders being filled with molten metal, the latter is forced right into the finest lines

of the mold, thus giving a firmly molded denture accurately impressed in every detail.

By the provision of the bell-shaped cover with the perforate partition or baffle *i*, said 50 cover is divided into upper and lower air chambers or compartments, the lower chamber of the cover being adapted to receive the upper ends of molds which are of greater height than the mold chamber of the receptacle, so that one or more molds of varying heights may be accommodated for molding operations at one and the same time in the molding apparatus, and the upper chamber 55 of the cover communicating with the compressed air supply passage, whereby the tumbling current of air flowing into the upper chamber of the cover and passing downward through the perforations in the perforate baffle or partition will be checked by 60 the baffle and converted into straight vertical line streams and pulsations or variations in the pressure of the air thus supplied to the mold receptacle prevented and the pressure rendered uniform for action on the 65 metal in the molds.

What I claim is:

In an air pressure apparatus for casting plates and duplicates thereof for dental purposes, the combination of a mold holding receptacle, a stationary solid base support carrying said receptacle, a pair of rack-toothed standards, a transverse bar connecting said standards at their upper ends, a cover of bell shape for closing the receptacle and having a perforated transverse partition dividing it interiorly into upper and lower chambers, said cover being fixed to said transverse bar, pinions meshing 75 with the rack teeth of the standards for 80 moving the same to shift the cover into and out of sealing engagement with the receptacle, one of the standards having an air duct for feeding air under pressure to the upper chamber of the cover for passage 85 90

through the holes in the transverse partition of said cover into the receptacle whereby the whirling air current entering the upper chamber of the cover is converted into straight line streams on its passage through said partition and the flowing air thereby checked and governed to secure a uniform air pressure upon the molten metal in the molds.

10. In testimony whereof I affixed my signature.

KARL DEHNE.
